UNITED STATES PATENT OFFICE.

HENRY MILTON MYERS, OF BEAVER FALLS, PENNSYLVANIA.

MACHINE FOR SPLITTING THE TANGS AND SHAPING THE BODIES OF SHOVEL-BLANKS.

SPECIFICATION forming part of Letters Patent No. 367,834, dated August 9, 1887.

Application filed March 21, 1887. Serial No. 231,740. (No model.)

To all whom it may concern:

Be it known that I, HENRY MILTON MYERS, a citizen of the United States, residing at Beaver Falls, in the county of Beaver and State of Pennsylvania, have invented certain new and useful Improvements in Machines for Splitting the Tangs and Forming the Sockets in Shovel-Blanks; and I do hereby declare the following to be a full, clear, and exact description of the invention, such as will enable others skilled in the art to which it appertains to make and use the same.

My invention relates to machines for splitting the tangs and forming the sockets in blanks for shovels, spades, and scoops, and has special reference to improvements in the splitting-machine shown in my Patent No. 348,037, dated August 24, 1886.

The invention will be hereinafter described, and particularly pointed out in the claims.

In the accompanying drawings, which form a part of this specification, Figure 1 represents a front elevation of my improved machine; Fig. 2, a side elevation. Fig. 3 is a plan view of the saddle. Figs. 4 and 5 are vertical sections of a modified construction. Figs. 6 and 7 are detail views of a blank and dies to be inserted in the saddle.

Reference being had to the drawings and the letters marked thereon, A represents an ordinary punching-machine having what is known as a "stop-motion," and in which machine is inserted a splitting knife or cutter, B.

C represents a saddle detachably secured to the machine by bolts *a*, and between the side walls, *b*, is formed a groove in which blocks or cheek-pieces *d*, *e* and rollers *f*, *g* operate to clamp the tang-supporting jaws *h*, *i* against the blank D. The upper ends of the jaws *h*, *i* are cut away, as shown at 1, 2, to form supports for the arms 3, 4 of the tang when rolled out to form the handle-straps of the shovel. The jaws are attached to the reciprocating head by right-angled hooks 5, 6, and project down through the saddle into the base of the machine.

On each side of the head is attached a lever, *k*, which is pivotally connected to links *l*, *l*, forming a toggle-lever. The opposite ends of the links *l*, *l* are connected to the rollers *f*, *g* by a pin or bolt passing through them, and the

rollers are connected to the blocks *d*, *e* by straps or links *n*, *n* for drawing the blocks away from the jaws *h*, *i* to release the blank D after the tang has been split.

Upon the saddle C is formed an anvil, *o*, and upon the head of the machine is a hammer, *p*, for closing the arms 3, 4 of a split tang.

E, F, in Figs. 6 and 7, represent anvils, the former having a concave upper surface, *r*, and the latter a convex surface, *s*. The anvils are inserted in the saddle C for the blank D to rest upon while being split and to impart to the lower edge, *t*, of the blank a convex or a concave surface, according to the kind of shovels being made, whether square or round points or ends. I do not, however, limit myself to this particular means for sharpening the blank, as it may be cut into the form shown in the drawings, or it may be thus formed in dies before it is inserted in the splitting-machine.

In the manufacture of shovels it is well known that in rolling a blade longitudinally the end of the blade forms a semicircular or an irregular line. Therefore to provide against such a formation in the one end and to increase the rounded point in the other the blank is formed as shown, either convex, as in Fig. 6, for round-point shovels, or concave, as in Fig. 7, for square-point shovels. The anvils are interchangeable, and can be easily and readily adjusted upon the saddle.

In another application filed herewith, Serial No. 231,741, the blank having a concave or convex lower end is claimed as a new article of manufacture. In Figs. 4 and 5 are shown a modification, and in which the tang-supporting jaws *h*, *i* are beveled in the reverse direction at their opposite ends. The lower ends, 7, 8, work upon correspondingly-beveled blocks 9, 10 in the base of the machine, and the upper ends, 11, 12, engage with correspondingly-beveled ends of pieces 13, 14, which are secured to the head of the machine. The jaws *h*, *i* are also secured to the pieces 13, 14 by bolts 15, which work in elongated slots 16 in said pieces 13, 14. The jaws *h*, *i* in both constructions reciprocate with the head and clamp the blank D while the tang is being split, and at the same time the upper or cut-away portions, 1, 2, of the jaws support the arms 3, 4 of the tang.

By the jaws moving with the head and the arms 3 4 being supported laterally the knife B advances into the tang evenly and prevents its running off to one side. The knife is forced down a sufficient distance to form the socket in the body of the blank for the reception of the tapered end of a wooden handle.

In the construction shown in Figs. 1 and 2 the reciprocating head operates the toggle-levers, and in its descent forces the rollers f g and the blocks d e against the jaws h i, which clamp the blank D and support the arms 3 4 of the tang. The upward movement of the head draws the toggle-lever toward the machine and blocks d e away from the jaws h i, which releases the blank D. The blank is then removed by the operator, and a little cinder thrown into the socket and between the split tang, after which the tang is placed upon the anvil o, when it is struck by the hammer p, and the arms 3 4 closed. The blank is then passed onto the rolls employed for reducing it to the shearing-point.

Having thus fully described my invention, what I claim is—

1. In a machine for splitting shovel-blanks, a reciprocating head provided with a cutter, in combination with tang-supporting jaws connected to the head and moved synchronously therewith, substantially as described.
2. In a machine for splitting shovel-blanks, a reciprocating head provided with a cutter, in combination with tang-supporting blank-clamping jaws connected to and reciprocating

with the head and moved laterally to clamp the blank by mechanism connected to the head, substantially as described.

3. In a machine for splitting shovel-blanks, a reciprocating head provided with a cutter, in combination with tang-supporting blank-clamping jaws connected to the head, and a toggle-lever attached to the head and operating to move the jaws laterally to clamp the blank, substantially as described.

4. In a machine for splitting shovel-blanks, a reciprocating head provided with a cutter, in combination with tang-supporting blank-clamping jaws connected to the head, levers connected to the sides of the head and carrying rollers at the opposite ends, and movable blocks operated by the levers to move the jaws laterally, substantially as described.

5. In a machine for splitting shovel-blanks, an anvil for forming concave or convex surfaces on the blank while the tang thereof is being split and the socket formed, substantially as described.

6. The combination of a reciprocating head, an anvil having a concave or a convex upper surface, and clamping devices for holding a shovel-blank, substantially as described.

In testimony whereof I affix my signature in presence of two witnesses.

HENRY MILTON MYERS.
